GOBLET OR SIMILAR ARTICLE

George L. Traner, Barrington, Ill., and Don A. Schreckengost, East Liverpool, Ohio, assignors to Royalon, Inc., Sebring, Ohio, a corporation of Ohio

Filed Apr. 6, 1964, Ser. No. 79,370

Term of patent 14 years

(Cl. D36—8)

FIG. 1 is an elevation of a goblet or similar article, showing our new design;

FIG. 2 is a top view thereof;

FIG. 3 is a bottom view thereof;

FIG. 4 is an enlarged detail of an elevation of one of the facets and the surrounding surface of the design, and

FIG. 5 is an enlarged sectional view taken along line 5-5 of FIG. 1.

We claim:

The ornamental design for a goblet or similar article, substantially as shown.
